CLEAR ICE-MAKING MACHINE

Theodore Kattis, Bedford, Ind.

Application April 12, 1950, Serial No. 155,433

9 Claims. (Cl. 62—2)

1

This invention relates to a machine for making ice in relatively small quantities, and particularly to the making of clear ice such as is preferred for use in icing drinks served in glasses and the like. The machine is preferably designed to be placed upon a counter such as at a soda water fountain, so that the ice may be made at the site of the soda water fountain, and only a small quantity of the ice need to be stored since the machine is so designed as to replenish the supply in a minimum amount of time.

While as above indicated, the primary object of the invention is to make clear ice, free of opaque spots or solid portions, gas bubbles, and the like which are objectionable in appearance in the icing of drinks. Furthermore it is an object of the machine to provide the ice in flake form so that it may be easily stored in sufficient quantity without intervening air spaces and at the same time fed from the storage into glasses and the like as may be desired. That is to say, the machine is not intended to make the commonly known ice cubes, but is intended to make ice in the flake form.

A still further important object of the invention is to provide a machine that is entirely automatic in character so that the ice storage will be automatically replenished when ice is withdrawn therefrom to a certain degree, and also that the ice making process itself will be discontinued when that storage space is filled to a predetermined level.

A still further important object of the invention is to provide the required amount of water without an excess to any great extent, and to do so automatically all within complete control of the mechanism of the machine itself once it is set into operation.

These and many other objects and advantages of the invention will become apparent to those versed in the art in the following description of one particular form of the invention as now best known to me, as illustrated in the accompanying drawings, in which:

Fig. 1 is a view in vertical central section fore and aft of the machine;

Fig. 2 is a view in vertical transverse section on the line 2—2 in Fig. 1;

Fig. 3 is a view in horizontal section on the line 3—3 in Fig. 1;

Fig. 4 is a detail in horizontal transverse section on the line 4—4 in Fig. 1;

Fig. 5 is a detail in front vertical elevation and partial section of the ice cutter mechanism;

2

Fig. 6 is a detail in vertical section on the line 6—6 in Fig. 5;

Fig. 7 is a view in outside perspective of the ice flow chute; and

Fig. 8 is a schematic wiring diagram of the control circuits.

Referring to the drawings, in which like characters of reference indicate like parts throughout the several views, there is spaced above a floor 10 a platform 11 on which the driving mechanism is mounted. An electric motor 12 is supported to have its armature shaft horizontally disposed transversely across the device, and to drive a gear 13, herein shown as a bevel gear, which gear 13 is in constant mesh with a bevel gear 14 fixed on a horizontally disposed shaft 15. This shaft 15 is generally supported by the brackets 16 and 17 secured to the floor 11. The bracket 17 in the present instance constitutes a side wall of a transmission housing which will be described later.

There is fixed on the shaft 15 a worm 18 which is in constant mesh with a worm wheel 19 that is secured to a vertically disposed shaft 20. The shaft 20 extends downwardly to traverse a pedestal 21 carrying bearings 22 and 23 at the top and bottom ends thereof respectively. The pedestal 21 is fixed to the floor 11, and the shaft 20 extends revolvably therethrough and on down through the floor 11 to have a cup 24 fixed to its lower end, and preferably reinforced at the interconnection by means of the gussets 25. The cup 24 being thus rigidly connected to the lower end of the shaft 20 turns therewith. Inside of the cup 24 there is positioned in a fixed manner a helical coil of tubing 26. Spaced to extend radially from the outer most portions of the turns of the coil 26 are a series of fins 27. The cup 24 is provided with a plurality of fins 28 to pass freely between upper and lower fins 27, as a means of agitating a brine solution which is designated by the numeral 29 and carried within the cup 24. The coil 26 carries a refrigerant, which enters and flows therefrom through the tubes 30 and 31, Fig. 3, which extend upwardly and are carried through the floor 11 and off through the machine cover 32. The bottom of the cup 24 is preferably provided with an insulating pad 33, enclosed by a metallic cover 34 exposed across the underside of the cup to give, preferably a smooth surface thereacross. The cup 24 is revolved through the shaft 20 to turn around the stationary coil 26, with the brine 29 inside thereof and agitated

and stirred by the relative interpassage of the fins 27 and 28 adjacent the outer wall of the cup 24.

In axial alignment with the shaft 15, is a shaft 36 supported by an outer end bracket 37, and by a bracket 38 which forms the side of the transmission housing 39 removed from the side 17 above mentioned.

The shaft 15 has fixed on its end within the housing 39 a pinion gear 40 to receive centrally therein the end of the shaft 36. In other words the gear 40 forms a pilot bearing for the extreme end of the shaft 36 inside of the housing 39. This gear 40 has fixed thereto on one side thereof a clutch faced plate 41 so that the plate 41 revolves with the gear 40.

A pinion gear 42 is revolutely mounted on the shaft 36 inside of the housing 39 adjacent the bracket 38. A clutch faced plate 43 is fixed to the gear 42 on that side which is presented toward the clutch plate 41. These two clutch plates 41 and 43 are spaced apart a distance to receive therebetween a shiftable plate member 44. This member 44 is slidably engaged to the shaft 36 to be revolved therewith, but capable of being axially shifted therealong between the plates 41 and 43.

A clutch shifting finger 46 enters an annular groove 45 around the member 44, and extends upwardly through the housing 39 to serve as a means for shifting the member 44 into selective engagement with either plate 41 or 43, or into the central neutral position as indicated in the drawing, Fig. 1, where neither plate 41 nor 43 is in driving contact with the member 44.

A jack shaft 47 is revolutely carried between the two brackets 17 and 38, and below the shaft 36, but in parallel alignment therewith. A pinion gear 48 is fixed to the shaft 47 and is in constant mesh with the gear 40. A second pinion gear 49 is fixed to the shaft 47 and is in constant mesh with an intermediate gear 50 which is carried within the housing 39 revolutely mounted on the post 51. This gear 50 in turn is in constant mesh with the gear 42. Thus with the shiftable member 44 in the position indicated in Fig. 1, turning of the shaft 15 will not drive the shaft 36. A reverse drive is set up through the pinion gears 40, 48, the shaft 47, pinion gears 49, 50, and 42, only when the members 44 and 43 engage.

A worm 53 is fixed to the shaft 36 between the brackets 38 and 37, to be in constant mesh with a worm wheel 54 which in turn is fixed to a vertically disposed shaft 55. This shaft 55 is revolutely carried through a fixed arm 56 extending from the bracket 37, to extend downwardly therefrom freely through the floor 11, and be guided by its lower end by a bracket 57 that is supported from the back wall 35 of the device. The shaft 55 is parallel to the shaft 20. A worm 58 is fixed to the shaft 55 to extend along its major length under the floor 11, and above the bracket 57.

This worm 58 is in the nature of a lead screw. The worm 58 in the form herein shown, is an integral part of the shaft 55. A nut 59, Fig. 4, slidably engages around the worm 58 and carries a spring pressed pin 60, the head of which engages within the helical groove 61 of the worm 58. The nut 59 is in the nature of a sleeve and has fixed integrally thereto a pair of forwardly extending and diverging arms 62 and 63. On the outer and forward ends of these arms 62 and 63 are brackets 64 and 65 respectively slidably receiving therethrough the vertically disposed

guide posts 66 and 67, the ends of which are secured respectively to the floor 10 and the platform 11, Fig. 2. These brackets 64 and 65 are secured to a water cup 68 so that when the nut 59 is carried along the worm 58, the cup 68 will be elevated and lowered accordingly. The water cup 68 has a conical floor 69, and also a frustoconical hood 70 at its top end. The cup 68 is cylindrical in shape, and has a diameter exceeding that of the refrigerating cup 24. The upper end of the hood 70 comes in to have a diameter closely approaching that of the outside of the cup 24. A cutter ring 71 is inserted and fixed in position in the upper mouth end of the hood 70. This ring 71 has a diameter which will permit it to be shifted upwardly along and around the cup 24 with a slight clearance therebetween, such as around about $\frac{1}{64}$ of an inch approximately. On the top edge of the cutter ring 71 is a frost cutter tooth 72, and on the under side of the ring 71 there extends downwardly and inwardly one or more ice cutting teeth 73, herein shown as three in number. The purpose of these teeth 72 and 73 will be further explained in the operation of the cup 68.

Axially extending downwardly from the floor 69 is a nipple 75 through which is guided a valve stem 76. This stem 76 carries on its upper end a valve head 77 seatable upon the seat 78 in the upper end of the nipple 75. The valve stem 76 is fluted to have the spaced apart vertical grooves 79 extending from under the head 77 downwardly throughout the length of the stem part 76. In order to prevent circumferential rotation of the stem 76, some restraining means is employed, herein shown as a screw 80 passing through the side of the nipple 75 and entering one of the flutes 79.

The stem continues downwardly from the fluted portion 76 by a reduced diameter stem 81 around which is positioned a coil spring 82 bearing against the washer 83 fixed to the lower end portion of the stem 81, and by its upper end against the lower end of the nipple 75 so that the spring 82 will normally tend to seat the head 77 against the seat 78. However when the cup 68 is in its inoperative position as shown in Fig. 1, the lower end of the stem 81 rests against an abutment 84 to hold the head 77 at a distance spaced above the seat 78 so that fluid flow may be had from inside of the cup 68 down through the flutes 79 out through the nipple 75 to discharge into a drainage cup 85 which is carried on the floor 10. A drain pipe 86 is provided to extend through the floor 10 from the cup 85.

The cup 85 has fixed thereto a stand pipe 87 which is turned vertically to receive therein in a sliding telescoping manner an overflow pipe 88, the upper end of which is fixed to the upper end of a chamber 89 fixed on the outside of the cup 68. There is a communicating passageway 90 in the wall of the cup 68 from the chamber 89. Thus when fluid is placed in the cup 68, with the valve head 77 seated on the seat 78, the maximum possible level of the fluid within the cup 68 is determined by the overflow pipe 88 leaving the chamber 89, discharge from that overflow 88 being within the stand pipe 87, and discharge therefrom being into the cup 85.

A water supply pipe 92 enters the side wall 35 and is carried upwardly to the platform 11, and then curved around downwardly by an end portion 93 in vertical alignment with the chamber 89, which chamber is open at its top end. The pipe 92 carries a shut off valve 94 in the

uprising portion thereof, this valve 94 being opened by a push button 95 normally spring pressed to a closed condition. On the lower end of the pipe portion 93 is fixed a spring scraper 96 so aligned that it will scrape the inside wall of the chamber 89, that wall being removed from the wall of the cup 68. On the forward side of the wall 35 is located an ice storage compartment 97. This compartment 97 carries an insulation wall 98 therearound. The compartment 97 terminates by an underside floor 99 spaced above the floor 10 a distance sufficient to permit the insertion under that floor 99 of a glass or cup to receive ice.

In axial alignment with the shaft 15 is a feed shaft 100 carried by the forward bearing 101 mounted on the upturned bracket 102, and a rearwardly placed bearing 103 carried in the upper end of the bracket 104. On the forward end of the shaft 15 is mounted a clutch plate 105 to be 15 shiftable longitudinally of the shaft 15, but to be driven thereby. On the rear end of shaft 100 is a companion clutch plate 106, fixed to the shaft 100, so that the plate 105 may be pulled compressively against the plate 106 in order to drive the shaft 100 from the shaft 15. A shifting fork 107 engages about the hub 108 of the plate 105 and extends upwardly therefrom into fixed engagement with a shifting rod 109 longitudinally supported through the forward part of the wall 32, loosely therethrough, and slidably through a guide arm 110 on the top side of the bracket 106. This shifter rod 109 extends externally of the wall 32 and is pivotally connected to an upper end portion of a lever 111, in turn rockably supported by its lower end on a bracket 112, in turn fixed to the outside of the wall 32. The upper end of the lever 111 carries an operating knob 113. Normally a spring 114 bearing between a pin 115 in the rear end of the rod 109 and the back side 40 of the member 110 holds the shifter rod 109 in its rearmost position so as to separate the plate 105 from engagement with the plate 106, as indicated in Fig. 1.

The shaft 100 has a worm 117 fixed thereon to be in constant mesh with a worm wheel 118 which in turn is fixed to the upper end of a vertically disposed shaft 119. This shaft 119 extends vertically downwardly through the floor 11, the insulating partition 120 above the compartment 97, and down through that compartment 97 to carry on its lower end a feed auger 121. This auger 121 fits loosely within a bore 122 provided through the floor 99. The shaft 119 carries above the auger 121 a plurality of agitating vanes or paddles 123. As indicated in Fig. 1, these paddles or veins 123 are provided at least at two different elevations.

As indicated in Fig. 1, and also in Fig. 3, the cross-sectional shape of the upper part of the compartment 97 is generally U-shaped, with the legs thereof turned rearwardly toward the wall 35 to engage therewith. Across the opening between those two legs designated by the numerals 124 and 125, Fig. 3, is positioned a door 126. This door 126 is preferably insulated, and is fixed to the cup 68, herein shown as being engaged to the upper hood 70. The compartment 97 has a window 128 opening through into the space within the wall 35, this window being generally of the same dimensions as that of the door 126, so that when the door 126 is in a lower position as indicated in Fig. 1, the window 128 is closed so that the compartment 97 is substantially insulated from the space within the wall 35. Practically 70

there is a slight clearance provided between the wall 35 and the forward face of the door 126 so that the door 126 may be moved vertically in relation to the wall 35, and on the inside thereof.

Further explanation of the structure will be better understood in connection with a description of the over-all operation as now follows.

Operation

Referring to Fig. 8, the motor 12 is connected across the power lines 130 and 131 through an intervening switch 132. This switch 132, Fig. 1, is located to have its operating member in the path of the lever 111 so that when the lever is in the position as indicated in Fig. 1, the switch is normally opened, but will close automatically when the lever 111 is pulled outwardly to cause the clutch plates 105 and 106 to come into driving interengagement.

With the lever 111 pulled outwardly, the motor 12 is set into operation and the shaft 119 is thus revolved, and any ice in the compartment 97 will be fed outwardly and downwardly therefrom through the bore 122.

At the same time the shaft 119 is being driven, the shaft 20 is likewise being driven to revolve the cup 24 around the refrigerating coil 26. The clutch member 44 is in the neutral position as indicated in Fig. 1, so that while the shaft 15 is turning, the shaft 36 will not be turned thereby.

Within the compartment 97, there is located a thermostat switch element 133, so positioned that when the ice within the compartment 97 drops therebelow, this member 133 will close, first a circuit from the wire 131 through the wire 134 through the switch arm 135, the contact 136, the wire 137, and the wire 138 to the motor 12 which in turn is connected to the wire 130. Assuming that the ice has been delivered from the compartment 97, and the thermostat element 133 exposed above any residual ice in the compartment 97, and the lever 111 is released to open the switch 132, the motor 12 is thus set into operation through that switch member 135 of the thermostatic element 133. The operation of the motor revolves the shaft 20 as before indicated.

This thermostat element 133 also closes another circuit from the wire 131 through the wire 139, the switch member 140, the contact 141, the wire 142, a solenoid magnet 143, a wire 144, leading to a fixed position contact 145, a switch arm 146, and a wire 147 connected to the wire 130. The arm 146 is normally urged into contact with the contact member 145 by means of the spring 148.

The clutch shifting finger 46 is fixed to the iron armature 149 which is slidable within the solenoid 143, so that when the solenoid 143 is energized under the circuit conditions just described, the finger 46 will be shifted to the left, Fig. 1, to bring the member 44 into engagement with the clutch member 41. The gear 42 turning on the shaft 36 remains meshed with the gear 50. This interconnection between the members 41 and 44 directly connects the shaft 36 with the shaft 15 so as to turn the shaft 55 and consequently the worm 58 thereon.

With the shaft 55 thus turning, the nut 59 will start climbing along the worm 58. Normally when the nut 59 is in its lowermost position, Fig. 1, it is bearing against a limit switch 150 so as to hold that switch open. Therefore when the nut 59 starts rising vertically, the limit switch 150 automatically closes. The closure of the switch

in this particular cycle does not affect any reconditioning of the circuits so far described.

As the nut 59 rises, the cup 68 is likewise carried upwardly, and the valve head 77 is then permitted to seat on its seat 78. The nut 59 carries a cam 151 which is in the path of the water valve operating button 95, so that after a predetermined initial travel upwardly of the cup 68, this cam 151 comes up to push the button 95 into the open valve condition, whereupon water will start to flow from the supply pipe 92 and outwardly from the water line portion 93 into the compartment 89, and consequently into the cup 68.

As the cup 68 rises, the cutter ring 71 traverses the outer wall of the cup 24, with the tooth 72 coming into close engagement therewith to shave off any frost which may have been formed around the cylindrical portion of the cup 24.

As indicated in Fig. 4, there is a frost discharge chute 153 fixed to the outer side of the cup 68, to turn back under the floor 69, to permit any frost coming down that chute 153 to fall into the sump collecting cup 85. The tooth 72 is located in reference to the chute 153 as best indicated in Fig. 4 whereby the shaved off frost will drop down that chute.

The cup 68 will be continued to be lifted by the nut 59 until the nut reaches that position along the worm 58 whereby the pin 60 reaches the top circumferential groove 154, Fig. 1. Since further upward travel is prevented by reason of the presence of this circumferential groove 154, the nut 59 will come to a rest in respect to vertical travel at this position while the shaft 55 continues to revolve. With the cup 68 elevated to that corresponding position, the water level in the cup 68 will have been brought up to the over-flow pipe level, that is the level of the top end of the pipe 88, so that the refrigerating cup 24 will then be revolving within the cup 68 with the water level therein maintained at that height. It is to be noted that the length of the cam 151, is made to be such that there will be a dwell period in riding over the button 95 sufficient to carry an excess amount of water through the cup 68 to flush it out, and at a predetermined level thereabove of this cam 151, the button 95 will be free to return to the water flow cut off position.

When the cup 68 is in its uppermost position, the lower peripheral portion of the cup 24 will be revolving within a ring 156 which is fixed to the floor 69 inside of the cup 68. The internal diameter of this ring 156 is made to be such that the lower end of the cup 24 may revolve freely therein, but will also serve as a guide to prevent oscillatory motion of the cup 24, and also serve to prevent the formation of ice along that lower covered portion, which portion is externally of the insulating layer 33.

Also before the cup is finally received through the ring 156 to the relatively lowermost position, a frost cutter blade 157 comes into contact with the under side of the cup 24 to shave off any frost which may have collected thereon, so as to prevent an excessive building up of frost on that part of the cup 24. This cutter bar 157 is, in the present showing, mounted on a head 158 that is vertically reciprocable on a post 159 extending upwardly axially from the valve head 77. A spring 160 surrounds the head 158 to bear between the cutter bar 157 and the top of the valve head 77 in order to yieldingly urge the cutter bar 157 upwardly and also permit yield-

ing retraction toward the valve head 77 when contact of the cutter bar 157 is made against the under side of the cup 24. A pin 161 extends through a slot 162 in the member 159, and engages with the head 158 so as to limit the upward travel of the head 158. Also the pin 161 prevents turning of the head 158 relative to the valve head 77 so that the cutter 157 remains stationary in respect to rotation of the cup 24.

There is a plate 164 which is normally bearing against the circumferential wall of the cup 24. This plate 164 is fixed to the lower end of a rod 165 which is pivoted on a bracket 166 resting on the top side of the floor 11 above the cup 24. As indicated, the rod 165 is off set by the arm 167 so that normally the plate 164 will tend to swing toward the cup 24 when the wall of the cup 24 is positioned as indicated in Fig. 1 to be in the path thereof. The cup 68 clears the plate 164 by reason of a slot 190 being provided in the ring 71 and hood 70. In other words the plate 164 tends to ride in contact against the wall of the cup 24 under the influence of gravity. The purpose of the plate 164 is to change the cycle of operations when a predetermined thickness of ice builds up on the circumferential portion of the cup 24. The cup 68, carrying water, has the cup 24 relatively immersed in the water therein, and due to the refrigerant within the cup 24, ice will form on the revolving cup, to be free of bubbles and foreign matter, so that the ice forms in a clear form.

When the ice reaches the desired predetermined thickness, the plate 164 between which and the wall of the cup 24 the ice is forming pushes the plate 164 outwardly, to rock an upper arm 168 connected to the rod arm 167. Travel of the plate 164 away from the cup 24 causes the arm 168 to bear against the lower end of the switch 146 to rock that arm out of contact with the member 145 and into contact with a member 169.

Prior to that operation of the arm 168, when the limit switch 150 has been allowed to close due to the upward travel of the nut 59 therefrom, a circuit had been established from the wire 130 through the switch arm 170, the wire 171, a magnet 172, a wire 173, and a wire 174 which connects with the wire 131. While the magnet 172 has thus been energized, and the switch arm 146 carries an armature 175, that armature 175 is normally positioned by the switch arm 146 under the influence of the spring 148 to overcome any pull of the magnet 172. However when the arm 168 has rocked the switch 146, the spring 148 is overcome, and the armature 175 is pulled up to the magnet 172, and the magnet thereupon tends to retain the switch arm 146 in the shifted position to make contact with the member 169 even against the pull of the spring 148. This condition will be maintained even though the plate 164 thereafter tends to swing to the left, Fig. 8, that is until some other circuit condition is changed as will be hereinafter indicated.

When the switch arm 146 closes against the member 169, the solenoid 143 is deenergized, and a circuit is then set up from the wire 130, the wire 147, the switch arm 146, the contact member 169, the wire 177, the winding of a solenoid 178, the wire 174, and the other power line 131.

The solenoid 178 carries therein the opposite end of the armature bar 149, and therefore causes the finger 46 to be shifted to the right, Figs. 1 and 8, to separate the members 41 and

44, and to bring the member 44 into driving contact with the plate 43 and thus drive the shaft 36.

This change in drive between the shaft 15 and the shaft 36 sets up a travel of the shaft 36 in a direction reverse to that of the shaft 15, and thus reverses the travel of the shaft 55 and its worm 58 to cause the nut 59 to feed downwardly therealong. It is to be remembered that the cup 24 is continually revolving during these operations. When the nut 59 starts downwardly, the cup 68 is likewise started downwardly in relation to the cup 24. The teeth 73 carried by the cutter ring 71 being in very close proximity to the wall of the cup 24 start shaving the ice off of that cup 24. This shaved off ice flies off to fall into the chute 179. This chute is inserted through the hood 70 to have its inner upper end portion under the teeth 73, and is inclined to discharge from the outer side of the cup 68. The chute 179 is located immediately under the lower edge of the door 126. When the cup 68 was raised upwardly about the cup 24, the door 126 had likewise been lifted up through the floor 11, so that the window 128 was completely opened, and as the ice is being shaved off of the cup 24 by the teeth 73, the ice will drop through the chute 179 through the window 128 with the door 126 coming down to follow the travel downwardly of the teeth 73 until the lowermost position of the cup 68 is again reached when that window 128 will be completely closed.

Further, as the nut 59 lowers, the water valve 94 will again be opened to supply fresh water to the cup 68, to provide a reservoir of water so that when the cup 68 reaches its lowermost position, the valve head 77 will have been opened to the position indicated in Fig. 1, and all of the water dumped out through the nipple 75 into the cup 85, whereby all ice and frost accumulation within the cup 68 is flushed out. No ice can then form within the cup 68, although the space within the wall 35 might be brought down to freezing or below.

The ice cut off by the teeth 73 coming down 45 into the chute 179 drops into the compartment 97. If the supply of ice thus provided does not reach that elevation of the thermostat element 133, the cycles just described will be repeated. This is due to the fact that the limit switch 150 opens 50 by pressure thereon of the nut 59, while the thermostat switch arms 135 and 140 remain closed.

When that switch 150 opens, the arm 170 opens so as to deenergize the magnet 172, allowing the switch arm 146 to swing back into contact with the member 145, thus deenergizing the solenoid 178, and energizing the solenoid 143 for the reverse travel of the worm 58 to again lift the nut 59.

Should it occur that the thermostat element 133 be reached during these cycles by the ice piling up in the compartment 97, and thereby cause the arms 135 and 140 to open their respective circuits, the limit switch 150 which is in the closed position at any time the nut 59 is thereabove and out of contact therewith, still holds the arm 180 of that switch in a closed position so as to maintain the closed circuit through the wires 131 and 138 to provide current flow through the motor 12 in order to complete that cycle in which the apparatus may then be engaged, to the end that the nut 59 will finally come to its lowermost position. Then of course, the switch 150 is opened so that the arm 180 is 75

then in its open circuit condition so as to finally break the flow of current to the motor 12.

The shifting finger 46 is normally retained in a neutral position by means of the springs 191 and 192 interposed between that finger around the armature rod 149 and the solenoids 143 and 178. These are light springs, so that not too much energy is involved when the member 44 is to be shifted in either direction. It is to be seen that this particular means of direct and reversing drive of the shaft 36 tends towards a silent operation.

While I have herein shown and described my invention in the one particular and specific form, it is obvious that many structural changes may be employed without departing from the spirit of the invention. Such changes may be in the specific form of drive between the various members, the particular way of reversing travel of one member in respect to another, and the like. Therefore I do not desire to be limited to that precise form beyond the limitations which may be imposed by the following claims.

I claim:

1. An ice making machine comprising a refrigerating cup; a water cup; motor driven means for revolving the refrigerating cup; motor driven means immersing the refrigerating cup while being revolved in said water cup for a period to freeze water from the water cup on the surface of the refrigerating cup and then withdrawing the water cup from around the refrigerating cup; an ice cutter bearing toward said surface and traveling with said water cup to chip ice from said surface; a water supply line to discharge into said water cup; valve means controlled by travel of the water cup as said refrigerating cup is being immersed to fill said water cup from said line.

2. An ice making machine comprising a refrigerating cup; a water cup; motor driven means for revolving the refrigerating cup; motor driven means immersing the refrigerating cup while being revolved in said water cup for a period to freeze water from the water cup on the surface of the refrigerating cup and then withdrawing the water cup from around the refrigerating cup; an ice cutter bearing toward said surface and traveling with said water cup to chip ice from said surface; a water supply line to discharge into said water cup; valve means controlled by travel of the water cup as said refrigerating cup is being immersed to fill said water cup from said line; and water cup overflow means predetermining the maximum water level in the water cup.

3. An ice making machine comprising a refrigerating cup; a water cup; motor driven means for revolving the refrigerating cup; motor driven means immersing the refrigerating cup while being revolved in said water cup for a period to freeze water from the water cup on the surface of the refrigerating cup and then withdrawing the water cup from around the refrigerating cup; an ice cutter bearing toward said surface and traveling with said water cup to chip ice from said surface; a water supply line to discharge into said water cup; valve means controlled by travel of the water cup as said refrigerating cup is being immersed to fill said water cup from said line; valve means normally open for dumping water from said water cup; said second valve means being operated to closed condition by immersing travel of the water cup.

4. An ice making machine comprising a refriger-

11

erating cup; a water cup; motor driven means for revolving the refrigerating cup; motor driven means immersing the refrigerating cup while being revolved in said water cup for a period to freeze water from the water cup on the surface of the refrigerating cup and then withdrawing the water cup from around the refrigerating cup; an ice cutter bearing toward said surface and traveling with said water cup to chip ice from said surface; a water supply line to discharge into said water cup; valve means controlled by travel of the water cup as said refrigerating cup is being immersed to fill said water cup from said line; and frost cutter means carried by said water cup and bearing toward said refrigerating cup to remove frost from said surface during said water cup immersion travel.

5. An ice making machine comprising a refrigerating cup; a drive for revolving said cup; a water cup; a drive for lifting and lowering said water cup to immerse said refrigerating cup therein to have ice freeze on the surface and to lower the water cup to have the refrigerating cup removed therefrom; a motor to actuate both of said drives; means traveling with said water cup to remove ice from said surface upon lowering travel of the water cup; a compartment receiving ice from said ice removing means; an ice level responsive member in said compartment; an electric switch actuated by said member to open and closed conditions in accordance with predetermined high and low ice levels in the compartment; and an electric circuit including a source of energy, said motor, and said switch, to drive said motor upon a low ice level, switch closed condition to actuate said drives.

6. An ice making machine comprising the combination of a water cup; a refrigerating cup; drive means to revolve said refrigerating cup; drive means simultaneously shifting the water cup to telescope about the refrigerating cup and to withdraw the water cup from that telescoping relation; a frost cutter carried by said water cup to pass over the revolving surface of said

12

5 refrigerating cup during said telescoping shifting; ice cutter means interconnected to travel with said water cup to pass across said surface of said revolving refrigerating cup during said withdrawal of the water cup; an ice receiving member under said ice cutting means diverting ice removed thereby from over said water cup to a side thereof to maintain separation between removed ice and frost.

10 7. The structure of claim 6 wherein there is included frost collecting means apart from said ice receiving member.

15 8. A method of producing flake ice which comprises the steps of revolving a refrigerated cylinder; raising to a predetermined level a volume of water about said revolving cylinder to submerge the cylinder in part at least in the water to freeze ice on its surface; lowering said level of the water about the cylinder while still revolving; cutting ice from the cylinder above the level of the water as it is lowered and diverting the ice from above said level to a receptacle apart from said water.

20 9. The method of claim 8 wherein frost accumulating on said cylinder while out of said water is scraped off said cylinder prior to the cylinder submergence in the water, and the frost is withheld from entering the water.

25 THEODORE KATTIS.
